DOW B. HUGHES, OF CLEVELAND, OHIO, ASSIGNOR, BY DIRECT AND MESNE ASSIGNMENTS, TO THE CITIZENS SAVINGS AND TRUST COMPANY, TRUSTEE, OF CLEVELAND, OHIO, A CORPORATION OF OHIO.

DOUBLE IGNITION SYSTEM FOR INTERNAL-COMBUSTION ENGINES.

1,075,974.

Specification of Letters Patent.

Patented Oct. 14, 1913.

Application filed November 20, 1909. Serial No. 529,019.

To all whom it may concern:

Be it known that I, Dow B. HUGHES, a citizen of the United States, residing at Cleveland, in the county of Cuyahoga and State of Ohio, have invented a certain new and useful Improvement in Double Ignition Systems for Internal-Combustion Engines, of which the following is a full, clear, and exact description.

10 It is quite common practice to provide on automobiles driven by internal combustion engines, two electrical ignition systems, viz., one including a battery and spark coil, and the other including a magneto. In the use 15 of this double ignition system the battery circuit is employed for starting the engine. When the engine is well under way the operator by turning a switch breaks the battery circuit and completes the magneto circuit.

20 The object of this invention is to obtain all the advantages of this double system by an apparatus which does not require that the operator shall bother himself to turn a 25 switch to disconnect the battery system and to connect up the magneto system. The apparatus shown in the drawing embodying the invention realizes this object and indeed 30 produces better sparks from the second system than are obtained from the ordinary magneto, and does this with an apparatus which is less expensive than the double system heretofore used.

35 In the drawing, Figure 1 is a side elevation with certain parts of the casing broken away and sectioned. Fig. 2 is an end view from the left side of Fig. 1. Fig. 3 is an end view from the right side of Fig. 1. Fig. 4 is a sectional end view in the plane 40 indicated by line 4-4 on Fig. 1; and Fig. 5 is a diagrammatic view of the apparatus.

45 Referring to the parts by letters, A represents the framework on which the moving parts are supported.

B represents an ordinary alternating current generator having separately excited fields.

50 C represents a shaft which is to be connected with the engine in such wise that it rotates at cam shaft speed,—that is to say, in a four cylinder engine of the four-cycle type, at half the speed of the engine shaft. The generator is driven from this shaft by a train of gears shown partly by dotted lines

in Fig. 1, said train consisting of gear c 55 fixed to shaft C, a gear d fixed to a short shaft D mounted in the frame A, a gear d' fixed to this same shaft, and a gear b fixed to the armature shaft of the generator. The gears c and d are of such relative size that 60 the shaft D rotates four times as fast as the shaft C. The function of the shaft D is to operate what is commonly known in this art as the "timer," which is a device whose function is to make and break, at proper intervals, the circuit of the primary of the induction coil. There are a great variety of these timers, and the specific construction of that shown is not at all material to the present invention. The particular timer shown, 70 however, includes a pivoted contact lever F which is connected in the primary circuit of the induction coil, a spring contact bar G which is also connected in the same circuit, and a cam d² fixed to shaft D engaging with 75 the friction roller f carried by said lever, whereby in each revolution of the shaft D this lever is forced upward into contact with the spring contact bar G thereby completing the primary circuit of the induction coil. 80

At the right end of the shaft C, as shown in Fig. 1, is what is known as the distributor. This is an apparatus generically of well known form for conveying the secondary or high tension current in proper sequence to 85 the spark plug of the several engine cylinders. Any suitable distributor may be employed for the purpose. That which is shown consists of a disk Q fixed to shaft C and carrying a brush q. This disk is in a 90 cylindrical recess h in a block K of insulating material. As the shaft C rotates, the brush wipes against the interior cylindrical surfaces of metal contact plates set into this recess at points 90 degrees apart. Those contact plates are to be severally connected by means of conductors J with the several spark plugs of the engine cylinders. 95

By reference to Fig. 5, the circuits to be made and broken to the various parts are 100 clearly shown. In this diagram, L indicates the battery, and H the plug socket for the reception of a plug to close a break in the battery circuit. The current from the battery, when the apparatus is at rest, and 105 until the engine attains some predetermined speed, is through the wire g to the primary winding of the induction coil I to a brush 1,

thence over a bridge 5 to the brush 3, and thence by the wire g' back to the battery. When, however, the generator circuit is in use the battery current flows over wires g 5 and g^2 to the field winding B^2 , thence through wire g^3 to the other field winding B^2 , and thence to the brush 4, thence over the bridge 7 to the brush 3, and thence back to the battery by the wire g' . The generator 10 circuit is then from the collector ring B^3 over wire g^4 through wire g to the primary windings of the induction coil I, thence to the brush 1, then by the way of the bridge 6 to the brush 2, and thence by wire g^5 to the 15 other collector ring B^4 . The generator circuit and the battery circuit, when the motor is cut out, both include, as shown, the timer described. There is a shunt circuit including the wires g^6 , g^7 around said timer, and 20 leading to a switch g^8 , which switch may be operated by hand after the fashion of a vibrator to complete the circuit and thereby create a spark in one of the cylinders if the engine is self-starting,—that is to say, if one 25 of the cylinders has held a compressed charge of the explosive mixture while the engine has been idle.

The three bridge pieces 5, 6 and 7 are 30 fixed to the surface of an insulating cylinder M, which is in turn fixed to a shaft N mounted in suitable bearings carried by the frame member. The brushes 1, 2, 3 and 4 are arranged so as to contact with the surface of this cylinder and with the bridge 35 plates thereon when the cylinder is properly positioned. On one end of the shaft of this cylinder is a disk P carrying a pin p and on the outer end of the shaft of the cylinder is a small pointed cam n which is engaged 40 by a roller R mounted in the end of the spring arm r which presses said roller against the face of this cam. A disk T is loosely mounted upon the shaft N and it has an arc shaped notch t in its periphery so 45 placed that the pin p projects into the same between the two terminal shoulders of said notch. This disk has rigid with it an arm t' in the upper end of which two anti-friction rollers t^2 are mounted. These rollers lie on 50 opposite sides of an annular flange w carried by a sleeve W which is slidably mounted upon the shaft C. There is a spring V tending to push this sleeve to the left, as shown in Fig. 1.

55 U represents a centrifugal governor of a familiar form carried on the shaft C. This is merely a ring pivoted on pins u , which ring is connected by a link S with sleeve W. As the speed of the shaft C increases, this 60 governor ring will be swung into more nearly a plane at right angles to the shaft, and in so moving will move the sleeve W to the right, as shown in Fig. 1. This will cause the disk T to rock, and by pressing 65 against the pin p to turn the cylinder M

until, when the point of the cam n reaches the proper position relative to the roller R said cylinder will be, by the action of spring r , suddenly turned to the position which brings the bridges 6 and 7 in contact respectively with the brushes 1 and 2 and the brushes 3 and 4. This automatically breaks the battery circuit going to the induction coil, and completes the battery circuit going to the fields of the generator, and the generator circuit going to the induction coil. When the speed of the shaft C gets below the predetermined speed, the spring V, overcoming the centrifugal force acting on the governor ring will move 70 sleeve W in the contrary direction, thereby turning the disk P in the contrary direction, and causing the lower shoulder or end of the slot in its edge to push against the pin p , thereby turning the cylinder M in the contrary direction. When it has been turned far enough for the point of the cam n to slip past the center of the roller R, the spring r , 75 acting upon this cam, turns the cylinder quickly and thereby brings the bridge 5 80 therein into contact with the brushes 2 and 3, thereby completing the battery circuit to the induction coil. It is this last described position of the cylinder which may be called its normal position,—that is to say, it is the 85 position in which it is when the engine is at rest, but, as will be understood from the foregoing description, when the engine gets up speed so that the generator generates a suitable current, which may possibly be 90 when the engine shaft is turning at the rate of three hundred revolutions per minute, the cylinder M is operated so as to automatically disconnect the battery and connect the generator in the circuit with the 95 primary winding of the induction coil. When the engine slows down, the reverse or 100 normal connection is automatically brought about.

Having described my invention, I claim:

1. The combination of a battery, a mechanical current-generator having separately excited fields, electrical connections between said battery and the field of said generator, an induction coil, connections between the primary winding of said induction coil and said generator, connections between the battery and the primary winding of said induction coil, and switch mechanism for either making or breaking the connections between the battery and induction coil on the one hand, and on the other hand for at the same time breaking or making the connections between said battery and generator field, and between the 115 generator and said induction coil.

2. The combination of a battery, a mechanical current-generator having separately excited fields, electrical connections between said battery and the field of said 120 generator.

generator, an induction coil, connections between the primary winding of said induction coil and said generator, connections between the battery and the primary winding of said induction coil, switch mechanism for either making or breaking the connections between the battery and induction coil on the one hand and on the other hand for at the same time breaking or making the connections between said battery and generator field and between the generator and said induction coil, a centrifugal governor carried by a rotatable shaft, and means intermediate of said governor and switch mechanism for operating the latter.

3. The combination of a battery, a mechanical current-generator having separately excited fields, electrical connections between said battery and the field of said generator, an induction coil, connections between the primary winding of said induction coil and said generator, connections between the battery and the primary winding of said induction coil and switch mechanism for either making or breaking the connections between the battery and induction coil on the one hand and on the other hand for at the same time breaking or making the connections between said battery and generator field and between the generator and said induction coil, a centrifugal governor carried by a rotatable shaft, and means intermediate of said governor and switch mechanism for operating the latter.

20 generator field and between the generator and said induction coil, a make and break timing device connected in the circuit of the

primary winding of the induction coil, a distributor connected in the circuit of the secondary winding of said induction coil, and means for operating said timer and distributor at proper relative speeds.

4. The combination of a battery, a mechanical current-generator having separately excited fields, electrical connections including switch mechanism between said battery and the field of said generator, an induction coil, connections between the primary winding of said induction coil and said generator, connections between the battery and the primary winding of said induction coil and switch mechanism for either making or breaking the connections between the battery and induction coil on the one hand, and on the other hand for at the same time breaking or making the connections between said battery and generator field and between the generator and said induction coil, a centrifugal governor carried by a rotatable shaft, and means intermediate of said governor and switch mechanism for operating the latter.

In testimony whereof, I hereunto affix my signature in the presence of two witnesses.
